UNITED STATES PATENT OFFICE.

JOHN SHEPHERD, OF TOLEDO, OHIO.

ADJUSTABLE BED-BOTTOM.

No. 813,458.

Specification of Letters Patent.

Patented Feb. 27, 1906.

Application filed September 28, 1905. Serial No. 280,414.

To all whom it may concern:

Be it known that I, JOHN SHEPHERD, a citizen of the United States, and a resident of Toledo, in the county of Lucas and State of Ohio, have invented a new and useful Improvement in Adjustable Bed-Bottoms, of which the following is a specification.

My invention relates to bed-bottoms, and has for its object to provide a bed-bottom with an improved adjustable head-section that is simple in construction and adapted to be readily raised and lowered and firmly supported at various degrees of inclination from the main body portion of the bed-bottom without increasing or diminishing the distance between the tops of the springs.

A further object is to provide a light, strong, convenient, and durable bed-bottom having a movable head-section that is adapted to be pivotally raised and lowered with means to support and to automatically lock the head-section at any desired degree of inclination from the main body portion of the bed-bottom.

I accomplish these objects by constructing a bed-bottom as hereinafter described, and illustrated in the drawings, in which—

Figure 1 is a top view of a bed-bottom constructed in accordance with my invention. Fig. 2 is a side elevation of the same, and Fig. 3 is an enlarged detail view of the bail-stirrup.

In the drawings, 1 represents the main frame of a bed-bottom, which comprises the side stringers 2, the middle stringer 3, the cross-bars 4, and the head-end bar 5, cross-connecting the stringers. The side stringers 2 are arranged parallel with the middle stringer 3 central between and parallel with the side stringers, and the side stringers are cross-connected at right angles at the head end by the head-end bar 5, which is framed into the end portions of the stringers with the top of the bar flush with the tops and ends of the stringers.

6 represents the head-section, which comprises the side bars 7 and the cross-bars 8.

The cross-bars 4 are arranged parallel with and secured to the tops of the stringers at regular intervals from the foot end toward the head, and the cross-bars 8 are arranged in like manner at the same intervals and are secured to the tops of the side bars 7 from flush with the head end toward the foot, and

the side bars 7 of the head-section are of such length that when the head ends of the bars are flush with the head ends of the side stringers 2 and resting on the cross-bar 5 their inner ends extend to the nearest cross-bar 4. The side bars 7 are arranged slightly converging toward their head ends at such distance from each other that the inner ends of the bars pass freely, but not loosely, between the inner faces of the stringers 2, and when in such position the head cross-bar 8 is above the head-end bar 5 and the innermost cross-bar 8 is at the regular interval of the cross-bars from the next adjacent cross-bar 4.

The side stringers 2 are each provided with a slot 9, which extends horizontally and centrally lengthwise of each stringer from a point near the innermost cross-bar 4 to a point beyond the innermost cross-bar 8, and the inner end portions of the side bars 7 are provided with transverse orifices, through which and through the slots 9 extend the outward and oppositely angled and alined end portions 10 of the V-shaped bail 11, which at the apex is angled to form a locking-stirrup 12 at right angles to the plane of the arms 13 of the bail, the stirrup 12 being adapted to drop over the middle stringer 3 and support the arms in the plane of the slots 9, as shown in Fig. 3.

The side bars 7 are linked to the side stringers 2 by the link-rods 14, which have oppositely-angled end portions 15, pivotally secured, preferably by the nuts 15', respectively to the stringers and the side bars in suitable orifices transverse the stringers and the bars, the pivotal connection of the link-rods to the side bars 7 being between their pivotal connection to the stringers and the inner ends of the side bars and the body portions of the link-rods in their normal lowered position being between the side stringers and the converging side bars. Thus constructed, when the head-section is raised by lifting the head-end cross-bar 8 the links form shifting-fulcrums, which rise oppositely to the head-section and upon which the head-section pivotally turns as it rises, thereby drawing the inner ends of the side bars of the head-section forward. The inner ends of the side bars 7 of the head-section being pivoted on the journals 10 of the bail 11 and the journals of the bail being confined by and pivotally movable along the slots 9 of the stringers, the raising

of the head-section causes a constant increase of the angle of inclination of the side bars 7 to the stringers 2, a movement of the inner ends of the side bars and the bail-journals toward the head end of the bottom-frame along the slots of the side stringers, and the shifting of the bail-stirrup along the middle stringer toward the head end of the main frame. By reason of their construction and of their location between the side bars of the head-section and the stringers 2 the link-rods also form lateral braces for the head-section when in raised positions, which prevent the head-frame from swaying sidewise.

15 The head-end portion of the middle stringer 3 is provided with a toothed rack-plate 16, which is secured to the top face of the stringer. The rack-teeth are adapted to permit movement of the bail-stirrup toward the head and lock it against movement in the opposite direction. Thus constructed, when the head-section is raised to the desired angle from the main frame the bail-stirrup slides forward over the middle stringer 3 and drops by gravity into engagement with a tooth of the rack and locks the head-section in the desired position, in which it is firmly supported and braced by the joint action of the link-rods and the bail, the stirrup 12, engaging the middle stringer, and the arms 13 of the bail together forming a truss-brace for the inner end portions of the side bars of the head-section. To release the bail and permit lowering of the head-section, there is attached to the stirrup 12 of the bail a cord 18, which extends upward to a cross-bar 8 and along the cross-bar, through suitable guides, to one side of the head-section, where a pendent portion forms a convenient means of lifting the bail above the teeth of the rack by pulling on the cord.

As constructed, the stirrup 12 of the bail forms both a guide and a prompt and sure latch for the bail. The arms 13, diverging 45 from the stirrup, form truss-braces for the inner end portions of the side bars of the head-section, and their angled end portions 10 form pivots and slides for the bail and the inner end of the head-section, while the link-rods 14, form both supports and lateral braces for the head-section in raised positions, the combined effect of the bail and the link-rods being when the head-section is raised or lowered to produce a direct forward or rearward movement of the inner end of the head-section and the bail along the slots of the side stringers, it being apparent that with my form of bail and link-rods, by reason of the side engagement of the stirrup with the middle stringer and the lateral bracing of the link rods they prevent any side swaying of the head-section and the binding and friction which would thereby be produced. Such construction also makes it practicable to reduce the number and size of the stringers and

the weight of the bed-bottom without materially reducing its strength.

Upon the cross-bars 4 and 8 are mounted the cone-springs 19 at regular intervals on each bar and in cross-rows transverse the bars, and they are interconnected at their top portions by the helical springs 20, as shown in part in Figs. 1 and 2. It is manifest that so mounted the tops of the cone-springs 19 of the contiguous cross-bars 4 and 8 will remain substantially at the same lateral distance whatever angle of inclination is given to the head-section, for the reason that as the angle increases the movement is such that the tops of the springs of the cross-bar 8 are only tilted rearward from the plane of the springs of the main frame to the angle of the head-section as the bottom of the springs are drawn forward and upward in an arc, as shown in Fig. 2, and it is also manifest that the nature of the movement precludes the possibility of the springs of the head-section becoming interlocked with the springs of the main frame by the movement of the head-section, the flexibility of the interconnecting helical springs 20 permitting the adjustment of the tops of the springs of the head-section at an angle to the plane of the tops of the springs of the main frame without perceptible strain or tension thereof and without either crowding together or spreading apart the adjacent rows of springs of the head-section and the main frame.

I am aware that bed-bottoms having adjustable head-sections provided with a bail and link-bars and intended to have similar movement, as herein described, have been made and described in patents, and I do not herein broadly claim the means to produce such movement; but I am also aware that such bed-bottoms have been found impractical and unsatisfactory by reason of the liability of the head-section to sway out of alignment with the main frame, and thereby become frictionally locked in position where further pivotal movement of the head-section and the bail is prevented, and my invention consists in the improved construction herein described, whereby such defective operation is wholly prevented and the desired adjustability of the head-section is attained and made practical.

What I claim to be new is—

In an adjustable bed-bottom, the combination with the frame 1, having the slotted side stringers 2, the middle stringer 3 provided with the rack 16, and the head-section 6, having the side bars 7 of the V-shaped bail 11, having the stirrup 12 at the apex adapted to engage the rack and move along the top and sides of the middle stringer as a guide, and the truss-arms 13 diverging from the stirrup and having their outer end portions 10 angled oppositely in alignment and extended through the inner end portions of the side

bars of the head-section and through the slots of the side stringers at right angles to the side stringers, the angled end portions 10 forming both pivots and slides for the bail and the 5 side bars, and the link-rods 14 having end portions 15 angled opposite, and pivotally connecting the side bars to the side stringers, substantially as and for the purpose set forth.

In witness whereof I have hereunto signed my name in the presence of two subscribing ^{to} witnesses, his 25th day of September, 1905.

JOHN SHEPHERD.
